Primary Examiner — Jeffrey D Asch*(74) Attorney, Agent, or Firm* — Myers Wolin, LLC(57) **CLAIM**

The ornamental design for a handset speaker, as shown and described.

DESCRIPTION

FIG. 1 is a perspective view of a handset speaker showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures showing the unclaimed portions of a handset and the broken lines shown on the handset speaker including the unshaded regions therein are for illustrative purposes only and form no part of the claimed design.
